SOL EINSTEIN, OF CINCINNATI, OHIO, ASSIGNEE, BY MESNE ASSIGNMENTS, TO
CINCINNATI GRINDERS INCORPORATED, OF CINCINNATI, OHIO, A CORPORATION
OF OHIO.

GRINDING MACHINE HAVING BALANCED SPINDLE.

Application filed March 1, 1924. Serial No. 696,196.

This invention relates to grinding machines, especially of the type in which the feed is accomplished by the bodily movement of the grinding head towards the work.

5 In such machines, the grinding head is slidably mounted on a rearwardly extended guideway provided by the bed of the machine. On this guideway is the spindle which carries the grinding wheel and which also carries 10 a pulley or an equivalent device which receives the belt that maintains the spindle in a state of rotation. When the grinding wheel is pressed against the work to accomplish its grinding function, there is created 15 a tendency to twist the head bodily to a certain extent and this tendency is, from a standpoint of extreme precision, aggravated by reason of the very slight amount of looseness in the slideway of the head and by reason 20 of the fact that the pulley does not in the conventional design so receive the pull of the belt as to cooperate towards reducing the twisting tendency. Furthermore, in conventional machines, the feed-screw is habitually 25 so located as to aggravate the aforesaid tendency.

A primary object of this invention is to effect a re-design of these parts and to do so in such a manner that the grinding-wheel, 30 the pulley, the belt, the guideway and the feed-screw will cooperate to the end that the head will be substantially balanced against twisting tendencies during the grinding operation.

35 In grinding-machines of the motor driven type, the motor has heretofore been located either in an awkward or unsightly location with respect to the mechanism as a whole, or else it has been located inaccessibly. In motor-driven grinding-machines, the general proportions are quite massive and the motor is quite large in size, and it is important that these principal elements be compactly related not only to save space but also to contribute 40 towards an orderly appearance of the machine as a whole; and it is important that the commutator and the brushes of the motor may be inspected with facility, otherwise these features which are so consequential 45 to the efficient operation of the motor are very likely to become neglected by the user.

Other objects and advantages will be in part indicated in the following description

and in part rendered apparent therefrom in connection with the annexed drawings. 55

To enable others skilled in the art so fully to apprehend the underlying features hereof that they may embody the same in the various ways contemplated by this invention, drawings depicting a preferred typical construction have been annexed as a part of this disclosure and, in such drawings, like characters of reference denote corresponding parts throughout all the views, of which:

Fig. 1 is a grinding-machine in front elevation typifying this invention. Fig. 2 is a transverse section through line 2—2 of Fig. 1 showing more especially the transverse slide-way for the grinder head and the feed-screw which is located to act as a balance fulcrum. 70 Fig. 3 is a fragmentary detail in plan of a portion of the infeeding mechanism. Fig. 4 is a section through line 4—4 of Fig. 1 to represent how the table may be manually traveled by the user. Fig. 5 is a transverse 75 section through line 5—5 of Fig. 3 showing in section a detail of the power transmission for infeeding the grinding head. Fig. 6 is a rear elevation of the grinding head showing certain transmission gears at the rear thereof. 80 Fig. 7 is a transverse section through line 7—7 of Fig. 1 showing the pulley drive for the spindle arranged to exercise a rearward pull on the spindle; said pulley drive embodying an automatic belt tightener. Fig. 8 85 is a sectional detail of the pumping system for the coolant. Fig. 9 is a detail view illustrating the relative arrangement of the grinder-head guide-way and the feed screw.

Referring now to the drawings, E represents the bed of the grinding-machine. As shown by Fig. 1, the right hand end of the bed is provided with a large opening into which is inserted the body A of the electric motor employed as the source of power. A 90 flange-plate A² provides means for bolting the motor to the end of the bed E and this motor provides an end casting A' which furnishes the bearing for its shaft B. It should be noted that the commutator end of the motor is exposed thereby providing immediate access to the commutator and the brushes while a considerable portion of the motor is inserted in the end of the bed as shown. The shaft B of the motor is either 100 connected with or continues as a shaft E' and

this is the main power or master shaft of the machine. This shaft extends longitudinally through the bed of the machine and at its extreme left end carries a pulley B³ for the belt that operates the lubricant pump. A large pulley B' carries the belt 1 which drives the spindle of the grinding-wheel. A small sprocket-wheel B² carries the chain 5 which conveys motion to the transmission system for accomplishing the infeed.

Referring now to Fig. 7, there is shown in section a portion of the grinding-head C. This head being mounted on slideways 30 and 31 shown best by Figs. 6 and 9. The 15 slideway 31 is of the V-type and it (as well as the feed-screw which is coaxial with that slideway) is arranged in balanced relation between the pulley and the grinding wheel as will presently appear.

20 As shown by Fig. 7, a spindle 3 carries a pulley 2 which is located on the opposite side of the V-guide 31 from the grinding-wheel 4. An idler a is mounted within the grinder-head C and the belt 1 runs from the 25 pulley B' around this idler a and thence around the pulley 2 so as to exert a rearward pull on the spindle. A belt-tightener takes up the slack of this belt for all of the positions of the grinder-head; this belt tightener 30 consisting of an arm a² pivoted to the head C at a', and having an idler a⁵. A weight a⁴ operates through a pull-chain a³ to maintain the idler against the belt and take up its slack.

35 By comparing Figs. 1, 2, 6 and 7, it will be seen that the V-guide 31 occupies a position substantially in the central plane between the grinding-wheel 4 and the pulley 2. Consequently, inasmuch as the grinding-wheel and the pulley are both urged rearwardly with substantially equal forces (the one by the pressure of the work and the other by the pull of the belt) there exists a state of substantial equilibrium and the head is not subjected to material twisting forces and consequently rests **truly** and **easily** in its V-guide. There is thus no tendency to cramp and interfere with the infeed of the head and there is no pronounced tendency towards misalignment.

It will also be noted from Fig. 2 that the V-guide 31 in point of elevation is considerably nearer the spindle 3 than has been the practice heretofore. Consequently, the head is not subjected to any considerable overturning forces and, by examining Fig. 7, it will be observed that the pull of the belt is such as tends to pull the head down onto its V-guide and to hold it securely in the same.

The feed-screw 28, as shown by Figs. 6 and 9, is centrally aligned with the V-guide and consequently its push does not subject the grinding-head to any forces tending to lift the head out of said V-guide or to cramp the head against movement in said V-guide.

Furthermore, both the screw and the V-guide are located in the midplane between the grinding-wheel and the pulley and the screw therefore acts as the central fulcrum of a balanced lever and the head is correspondingly relieved from any twisting tendency. It is also to be noted that the feed-screw is located upon the V-guide in the central plane thereof and consequently its line of action is brought quite near to the spindle so that the head is subjected to the minimum amount of overturning force and whatever overturning force exists is compensated for by the oblique pull of the belt as shown by Fig. 7.

While various transmission systems may be employed for turning the feed screw, that shown on the drawings is compact and well arranged and may be described.

The chain 5 turns a sprocket-wheel 6 which is appropriately journaled in the bed. 85 The shaft of the sprocket-wheel carries a long pinion 7 which continuously meshes with the gear 8 of a three-gear cluster adapted to be shifted by a lever L to bring either one of its gears 8, 9 or 10 into mesh 90 with the respective gears 8^a, 9^a and 10^a to impart any one of three different speeds to shaft 11. As shown by Figs. 3 and 5, this causes the worm 12 to rotate and thereby is rotated the worm 13 which actuates an eccentrically mounted roller operating in a slot in the oscillating lever 14. These oscillations are in turn imparted to an exposed oscillating lever 15 which is provided with a radial slot 95 so that the link 16 may be adjusted thereto 100 to receive a variable throw. This link 16 in turn oscillates an arm 17 which carries a pawl 18 having a catch 19 for engaging the ratchet teeth of a wheel 20. A coaxial lever 21 is adjustably fixed to the ratchet-wheel 20 and 105 through intervening gearing which need not be described, accomplishes an intermittent but progressive rotation of the shaft 23 that extends from the front to the rear of the bed. A gear train composed of gears 24, 25 and 26 110 transmit the motion to the shaft 27 which is formed at its forward end into the feed-screw 28 which, in turn, engages the nut 27 that is fixed to the head C so that the head may thereby be advanced bodily to accomplish the 115 so-called infeed of the grinding-wheel.

The work represented by W is appropriately mounted on a carriage or work-support S which slides on longitudinal guideways at the front of the machine. The details of this mechanism need not be described inasmuch as any conventional carriage may be employed for supporting the work; it being merely noted that Fig. 4 shows a hand-wheel H arranged to turn a pinion h that engages a 120 rack R for feeding the carriage S. The carriage may, of course, be fed automatically by power in any appropriate manner.

Without further analysis, the foregoing will so fully reveal the gist of this invention 130

that others can, by applying current knowledge readily adapt it for various utilizations by retaining one or more of the features that, from the standpoint of the prior art, fairly 5 constitute essential characteristics of either the generic or specific aspects of this invention, and, therefore, such adaptations should be, and are intended to be, comprehended within the meaning and range of equivalence 10 of the following claims.

Having thus revealed this invention, I claim as new and desire to secure the following combinations and elements, or equivalents thereof, by Letters Patent of the United 15 States:—

1. A grinding machine comprising a bed provided with a horizontal guideway; a head 20 translatable supported on said guideway; a spindle journaled in said head; a grinding-wheel and a pulley spaced apart on said 25 spindle; a belt-drive exercising a rearward pull on said pulley; and a feed-screw arranged substantially midway between said wheel and pulley and substantially in the horizontal and vertical planes of said guideway as to act as a fulcrum and balance the 30 head against twisting under the pull of the belt and the pressure of the grinding-wheel on its work.

2. A grinding machine combining a bed having an upper substantially horizontal surface provided with a V-guide; a head 35 slidably supported on said surface and guided wholly by said V-guide; a bearing in said head arranged in the vertical plane of said V-guide; a spindle rotatably journaled in said bearing; a grinding wheel secured to said spindle at one side of said bearing; a driving pulley secured to said spindle at the opposite 40 side of said bearing; and means acting in the vertical plane of said V-guide, to translate said head on said guide.

3. A grinding machine combining a bed having a rearwardly extending transverse 45 slide-way; a head slideable thereon; a transverse feed-screw located mainly above the bot-

tom of said slideway; a spindle journaled in said head and located somewhat higher than said feed-screw; a grinding-wheel on said spindle at one side of the vertical plane of said 50 screw; and a pulley on said spindle at the opposite side of said plane, the relative distances of said wheel and pulley from said plane being such that the pressure of the grinding-wheel on the work will be substantially balanced by the pull of the belt on said pulley.

4. A grinding machine combining a shiftable head; a spindle journaled therein; a grinding-wheel at one end of said spindle; a 60 pulley on said spindle; cross-guides for said head extending transversely to said spindle substantially in coincidence with a vertical plane transverse to said spindle midway said pulley and said grinding-wheel; and an in-feed screw substantially in coincidence with said vertical plane.

5. A grinding machine having a rearwardly extended V-guide; a feed-screw above the bottom of said V-guide and in the vertical 70 plane thereof; and a grinding-head slidably directed by said V-guide and arranged to be fed by said feed-screw.

6. The combination of claim 5 in which a spindle has a bearing in said head in said vertical plane and which carries a grinding-wheel and a pulley on opposite sides of said bearing and at substantially equal distances therefrom.

7. A grinding machine combining a bed 80 having a horizontally disposed slideway and a single angular guideway spaced from said slideway; a head supported upon said slide-way and guideway and held against horizontal rotation by the latter; and a feed-screw located in the vertical plane of and adjacent said guideway and having a threaded engagement with said head.

In witness whereof, I hereunto subscribe my name.

SOL EINSTEIN.
